UNITED STATES PATENT OFFICE.

WILLIAM H. ELMER, OF BERLIN, WISCONSIN.

TURBINE.

SPECIFICATION forming part of Letters Patent No. 443,905, dated December 30, 1890.

Application filed March 27, 1890. Serial No. 345,536. (No model.)

To all whom it may concern:

Be it known that I, WILLIAM H. ELMER, a citizen of the United States, residing at Berlin, in the county of Green Lake and State of Wisconsin, have invented certain new and useful Improvements in Turbines, of which the following is a specification, reference being had therein to the accompanying drawings, in which—

- 10 Figure 1 represents a plan view of the turbine; Fig. 2, a vertical sectional view thereof; Fig. 3, a horizontal sectional view taken through the inlet-gates; Fig. 4, a detail horizontal sectional view of the wheel, taken on the line $x-x$ on Fig. 5; Fig. 5, a side elevation of the wheel; Fig. 6, a plan view showing another form of the gate-shifting devices, and Fig. 7 a perspective view in detail of one of the wheel blades or paddles.
- 15 The invention has relation to that class of turbines wherein the water is supplied to the periphery of the wheel through a series of tangentially-arranged passages extending entirely around its perimeter, and discharged from the periphery at a point below the inlet-gates through tangentially-arranged passages, as will be more fully hereinafter set forth.

The invention has for its objects the production of an apparatus that will be very durable and strong, and which will utilize to an eminent degree the force of the water and prevent any waste whatever, as will more fully hereinafter appear.

In the drawings annexed, A designates a vertical cylinder flanged at its lower end and secured to the floor of the flume over the opening in the same. This cylinder tapers toward its upper end and is there provided with an inwardly-turned annular flange. Secured to or formed integral with this cylinder, near its lower end, is a horizontal frame or "spider" B, in the center of which the lower end of the wheel-shaft is stepped. In the side of the cylinder is formed an opening which is closed by a removable flanged plate or door C, whereby access may be had to the interior of the cylinder for cleaning and other purposes. One or more of these doors may be employed, but one will probably be found sufficient.

Supported upon and bolted to the upper flanged end of the casing A is the wheel-cas-

ing D, which is circular in shape and provided in its top with a central opening for the passage of the wheel-shaft. The casing 55 encloses the upper half of the wheel and is provided with lateral passages a, which carry the water into and project it against the wheel-blades in an approximately tangential direction, as shown most clearly in Fig. 3. Upon 60 one of the vertical side walls of each of the passages is seen a plate a', the outer vertical edge of which is extended beyond the periphery of the casing, and bent or curved backwardly, as at a'', forming a wide or flaring mouth to each passage. Fitted closely to the exterior of the casing are two rings E E, connected by vertical posts b, which latter are slightly concaved on their inner surfaces to fit closely the circular casing. The rings and 65 connecting posts or bars are preferably formed integral with each other, and the posts equal in number the inlet-passages a, as shown in Fig. 3. Secured to the rear side of each post is a plate b', which extends into 70 the adjacent passage nearly to the wheel and runs parallel with the adjacent vertical wall of the said passage. The rear sides of the posts and the outer ends of the plates secured thereto are curved outwardly, as at b'', to 75 assist in forming the flaring mouths of the inlets. The inner or adjacent faces of the rings E E are also curved or beveled off to assist in forming the wide mouths of the inlets, whereby the water may have a free un- 80 obstructed passage to the inlets. The forward vertical edges of the posts b are reduced or beveled off to fit behind the projecting curved lips a'' of the plates a', in order not to obstruct the inflowing water. To vary the 85 capacity of the inlet-passages the rings and posts are rotated in either direction. When the inwardly-projecting plates b' lie against the longer walls of the passages, the latter are open to their full extent. By rotating the 90 rings so as to bring the plates b' nearer the opposite walls of the passages the capacity of the same will be reduced, and by turning the rings far enough to bring the plates b' against the plates a' the supply of water to the wheel 95 may be entirely cut off. The advantage of 100 this particular arrangement of gates and passages is that the angle at which the water is projected is always the same whether the

gates be wholly or only partially open, whereby the full power of the quantity of water supplied to the wheel is utilized at all times.

To adjust the gate-rings rotatively I employ a pair of angle-levers *c* and pivot the same at diametrically opposite points on the top of the casing, the outer ends of the radial arms of these levers being connected to the top ring by means of oppositely-projecting pivotal links *c'*, and their other arms being connected together by a horizontal rod *c''*, as shown in Fig. 1. The pivot of one of the angle-levers is extended upward and forms a vertical shaft *d*, provided at its upper end with a hand-wheel *d'*, whereby the gates may be readily adjusted from the top of the flume. The advantages of this manner of adjusting the gates is that all gearing is done away with and the gate-rings are rotated smoothly without binding or undue wear. The old way of adjusting the gates by means of gearing is disadvantageous, in that the sand in the water soon grinds and wears the contacting surfaces to such an extent as to render the devices unreliable and unfit for use, and, further, because the power is only applied to one side of the rings, thereby causing them to bind and work hard, as is evident.

As shown in Fig. 6, I may employ two **T**-shaped levers instead of two right-angled levers and connect their oppositely-projecting arms by means of chains.

Leading out from the top of the casing is a pipe *e*, which is carried to one side and extended downwardly a suitable distance, whereby any water collecting upon the top of the wheel may find an exit and thus relieve the wheel of any pressure that would otherwise result from confined water.

The wheel consists of vertically-arranged radial blades *g*, secured between the curved faces of two conical-shaped hubs or disks *g'*, keyed upon the shaft a suitable distance apart. The blades are flat throughout their length, and are arranged in a vertical position and have formed integral with the lower portion of their outer edges extensions *g''*. These extensions are all curved and bent in the same direction—that is, away from the direction of the revolution of the wheel—so as to discharge the matter from the wheel in a tangential direction and into the tube or cylinder *A*. Surrounding the wheel about midway its length is a ring *h*, which is secured to the outer edges of the blades and to the upper ends of the lateral extensions *g''*, and which fits against the lower edge of the casing *D*, and thereby serves to greatly strengthen the wheel and steady it in its rotation.

The water in entering the wheel strikes first against the flat faces of the paddles and then again against the curved extensions of the paddles upon its discharge from the wheel, thereby exerting its utmost force upon the wheel.

The flat blades permit the water, after it exerts its initial force at the entrance to the wheel, to pass directly without obstruction to

the tangential discharge-opening formed by the bent portions *g''* of the blades. It will be observed that the advantages of a tangential feed and a tangential discharge are brought together and utilized to an eminent degree in this wheel.

The letter *h* designates a wooden step for the lower end of the wheel-shaft, which is provided with a lower reduced portion *h''*, fitted into a vertical central passage in the frame *B*, and an upper larger portion *h'*, which is recessed for the lower end of the shaft, as shown in Fig. 2. A vertical passage *h'''* may be formed in the step to let the water in under the shaft, and thereby prevent it overheating. This construction of step possesses advantages over the old form. Its principal advantage is that all lateral wear of the step is avoided, and the shaft is thereby kept in a true vertical position, free from binding, &c., until the step is entirely worn out; and a further advantage is that the water may circulate freely around the shaft and thereby prevent the binding and charring of the step, as is evident. In the old forms of steps, heretofore used, where the shaft rested on top of the step, it frequently happened that the shaft would work or wear to one side, especially where the wood was of an uneven texture, and thus cause the shaft to bind in its bearings in the casing; but my form of step obviates this trouble.

The special object I have in view in mounting the wheel-casing *D* on top of a cylinder resting upon the floor of the flume, instead of mounting it directly upon the floor, is to enable the wheel to be examined (by means of openings *C*) without having to take it up for that purpose.

Having described my invention, what I claim is—

1. The combination of a casing, a wheel enclosed therein, the gate-rings and gates, the angle-levers pivoted upon top of the casing at diametrical points, links *c'*, pivotally connecting the outer ends of the radial arms of the said angle-levers to the upper gate-ring, these links extending in opposite directions, a rod *c''*, connecting the parallel arms of the angle-levers, and a vertical-operating shaft *d*, formed by an extension of one of the pivots of the angle-levers, as and for the purposes described.

2. The combination of a vertical cylinder *A*, set upon the floor of the flume, over the opening in the same, and provided with an opening closed by a removable door, an open frame *B*, secured in the lower part of the cylinder *A*, a wheel-casing mounted on top of the cylinder, and a wheel-shaft stepped in the frame *B* and carrying a wheel, the said wheel extending from the wheel-casing into the cylinder *A* and having its lower end above the floor of the flume, as and for the purposes described.

3. The combination of a shaft, the conical hubs *g'*, keyed on this shaft a suitable distance apart and having their adjacent faces

concaved, vertical flat blades g , secured between these hubs, these blades being provided with lateral tangential extensions g'' on the lower portions of their vertical edges, 5 and a ring h , surrounding the wheel and secured to the vertical edges of the blades, substantially as described.

4. The combination of a shaft, the conical hubs g' , keyed on this shaft a suitable distance apart and having their adjacent faces concaved, and vertical flat blades g , secured be-

tween these hubs, these blades being provided with lateral tangential extensions g'' on the lower portions of their lower edges, substantially as described. 15

In testimony whereof I affix my signature in presence of two witnesses.

WILLIAM H. ELMER.
